UNITED STATES PATENT OFFICE.

FRANK E. JONES, OF KIRKWOOD, ILLINOIS.

DESIGN FOR A PAPER BOX.

SPECIFICATION forming part of Design No. 28,043, dated December 14, 1897.

Application filed October 16, 1897. Serial No. 655,483. Term of patent 3½ years.

To all whom it may concern:

Be it known that I, FRANK E. JONES, a citizen of the United States, residing at Kirkwood, in the county of Warren and State of Illinois, have invented and produced a new and original Design for a Paper Box, of which the following is a specification, reference being had to the accompanying drawings, forming part thereof.

10 In the drawings, Figure 1 is a view in perspective of a paper box, showing my new design. Fig. 2 is an end view thereof.

15 The leading feature of my design is a paper box shaped and ornamented to represent a child's cradle or crib.

20 The letter A designates the upper side, B and C the two sides, and D and E the two ends, of the box. The upper side A is slightly rounded transversely and is ornamented on its outer side with lines to represent the pillow and bedclothing of a cradle or crib. The 25 sides B and C have their outer sides ornamented with lines to represent the side body

of a cradle or crib. The ends D and E are extended upwardly above the plane of the 25 upper side A, terminating in a curved line, such extensions being ornamented upon their outer and inner sides with lines to represent, respectively, the head and foot boards of a cradle or crib, and said ends are also extended 30 below the plane of the bottom of the box, terminating in a curved line, said downward extensions being ornamented on their outer sides with lines representing the legs and rockers of a cradle or crib. The central portion of said ends is ornamented with lines to represent the end body of a cradle or crib.

I claim—

35 The design for a paper box substantially as herein shown and described. 40

In testimony whereof I affix my signature in presence of two witnesses.

FRANK E. JONES.
